UNITED STATES PATENT OFFICE.

KARL BAUMANN, OF URMSTON, ENGLAND, ASSIGNOR, BY MESNE ASSIGNMENTS, TO THE WESTINGHOUSE ELECTRIC & MANUFACTURING COMPANY, A CORPORATION OF PENNSYLVANIA, STEAM-TURBINE.

1,269,998.

Specification of Letters Patent. Patented June 18, 1918.

Application filed February 1, 1915. Serial No. 5,584.

To all whom it may concern:

Be it known that I, KARL BAUMANN, a citizen of the Confederation of Switzerland, and a resident of Urmston, in the county of Lancaster, England, have invented a new and useful Improvement in Steam-Turbines, of which the following is a specification.

One of the greatest difficulties experienced in connection with steam turbines, especially those of large size, is to insure that the steam shall pass quickly from the last row of blades through the casing to the exhaust pipe. Since in a horizontal turbine the opening from the casing into the exhaust pipe is in a plane approximately perpendicular to the plane of the last row of blades, the steam from the portion of the blading which is nearest the exhaust opening, the lower portion of the blading in a horizontal turbine, will meet the steam flowing in a different direction from the remaining portion of the blading, with the result that eddies are set up which seriously interfere with the uniform passage of steam to the condenser.

In order to obviate the above disadvantage the exhaust portion of the turbine casing is, according to this invention, partitioned off into separate compartments from each of which a passage leads to the exhaust orifice or pipe communicating with the condenser. Said passages are so arranged that, at the point at which they open into the exhaust orifice or pipe the steam passing through each of them will be flowing in substantially the same direction. In this way the formation of eddies due to the steam flowing in different directions from various portions of the last row of blades will be avoided.

By dividing up the exhaust in the manner just described, the exhaust portion of the turbine casing can, for a given output and efficiency, be reduced in size, with a consequent reduction in the cost of this part of the machine.

Looked at in another way the invention may be said to consist in the provision of one or more baffles or partitions in the exhaust portion of the turbine casing, so constructed as to separate the steam flowing from one portion of the last row of blades from that flowing from another portion thereof. Said baffles are continued along the exhaust portion of the casing sufficiently far

to insure that all of the steam escaping from the several portions of the last row of blades shall be flowing in substantially the same direction when it reaches the exhaust orifice or pipe.

One method of carrying out the invention is shown in the accompanying drawings in which Figure 1 is a longitudinal section of the exhaust end of a turbine in which the steam delivered from the last row of blades 60 B and in its passage to the exhaust opening is divided into four distinct streams. Fig. 2 is a plan view of the same, the upper half of the figure showing only the lower portion of the turbine. Fig. 3 is a sectional view 65 on the line III—III Fig. 2. Figs. 4 and 5 are transverse sections on the lines IV—IV and V—V respectively of Fig. 1. Fig. 6 is a shaded view of the end casing seen from the left of Fig. 1.

The end casing of the turbine consists of an upper portion 1 and a lower portion 2 united by flanges 3, 4 in the usual way. The upper portion 1 is divided at the top to form two cheeks 5 the inner parts of which meet 70 in a vertical edge 6 the inner portions of the flange 3 of each cheek being united by a semi-circular curve 7. Between these cheeks the upper part of the bearing housing is located. The upper and inner containing wall of the lower portion 2 of the casing is curved as shown at 8 to form a saddle shaped surface which, however, gradually merges into two inclined portions 9, 10 united at the bottom to form a web 11. Said inclined portions 9, 10 may be joined 75 by a transverse web 12 from which the lower part 13 of the bearing housing may be supported. The space between the inclined portions 9, 10 is closed by a transverse dia- 80 phragm 14 which unites at its inner and upper part with the saddle shaped surface 8 and is extended to unite at 15, 16 with the outer containing walls of the lower portion 2 of the casing. Said diaphragm is curved 85 toward the blading as shown clearly in Fig. 3 and finishes at the top by two straight edges 17, 18 (Figs. 4 and 5). The bottom edge 19 of the diaphragm extends across the exhaust port 20 as shown in Figs. 1, 2, 3 and 5. In front of the diaphragm, that is nearer to the blading, the web 11 may be continued by a web 21 extending from the curved portion 8 downward and joined at 22 to the lower portion 2 of the end casing.

100 105 110

Some idea of the shape of the four passages formed by the partitions above described will be obtained from the shaded view Fig. 6 which shows clearly that the steam issuing from the blading will be divided into four distinct streams which unite at the exhaust port 20 at which point, however, the steam in all the streams is flowing in the same direction. The steam being directed by gently curved surfaces the formation of eddies will be greatly reduced if not entirely eliminated.

In addition to directing the steam flowing from the last row of blades to the exhaust pipe, and thereby increasing the efficiency of the turbine, the partitions or diaphragms above described stiffen the exhaust portion of the turbine casing to a very material degree and make it possible to place the turbine bearing directly above the exhaust pipe. This is now done with turbines of comparatively small size, but with larger sized machines it would not be desirable to locate the bearing in this position in the absence of partitions or diaphragms such as those hereinabove described.

I am aware that in some cases in horizontal turbines a longitudinal vertical web has been employed for the purpose of strengthening the casing. Such a strengthening web has not, however, been continuous but has had one or more orifices therein, as is usual in strengthening webs of this kind. Whether such a web was continuous or not is, however, immaterial because in the first place such a web has not been constructed so as to divide up the exhaust steam in the manner contemplated by this invention, and in the second place a vertical web alone would not accomplish the object of this invention as it will be readily understood that with a vertical web the steam escaping from the upper portion of one half of the last row of blades would, as it passes downward to the exhaust port, be flowing in a different direction from that of the steam escaping from the blading in the lower half of the turbine, with the result that eddies would be formed, which it is the object and purpose of this invention to avoid.

What I claim is:

1. A steam turbine of the type in which the fluid discharged from the last row of moving blades changes its direction of flow in passing to the turbine exhaust port, comprising a rotor element, a stationary casing

inclosing the rotor and having an exhaust port formed therein, a plurality of exhaust passages formed within the casing, and located between the last row of blades mounted on the rotor and the exhaust port, each exhaust passage at any given instant receiving steam from less than the total number of blades.

2. A steam turbine of the type in which fluid discharged from the last row of blades is changed in the direction of its flow in passing to the exhaust port of the turbine, comprising a rotor element, a casing therefor having an exhaust port formed therein, substantially radially extending partitions located within the exhaust chamber of said casing and dividing the interior thereof into a plurality of exhaust passages, each communicating with the exhaust port, and each having a substantially segment shaped inlet which receives fluid from a portion only of the outlet of the last rotor wheel.

3. In a steam turbine in which the exhaust opening is in a plane perpendicular or substantially perpendicular to the plane of the last row of blades, radially extending partitions positioned within the exhaust chamber in such a manner as to subdivide the exhaust chamber into compartments for separately conveying portions of the steam flowing from the last row of blades to the turbine exhaust, to reduce loss due to eddies.

4. A steam turbine comprising a rotor, radially disposed blades mounted on the rotor, and a stationary casing provided with an exhaust port and surrounding the rotor and having an exhaust chamber formed therein in which fluid exhausted from the last row of radially disposed rotor blades changes its direction of flow in passing to the exhaust port, characterized by that a plurality of substantially segmental exhaust passages are formed within the exhaust chamber, between the last row of rotor blades and the exhaust port and are so arranged that each exhaust passage at any instant receives steam from less than the total number of the last row of rotor blades.

In testimony whereof, I have hereunto subscribed my name this twelfth day of January, 1915.

KARL BAUMANN.
